UNITED STATES PATENT OFFICE.

NATHAN M. BARR, OF NEW YORK, N. Y.

COMBINATION TRAVELING-CASE AND SALES-TABLE.

No. 808,427.

Specification of Letters Patent.

Patented Dec. 26, 1905.

Application filed May 22, 1905. Serial No. 261,613.

To all whom it may concern:

Be it known that I, NATHAN M. BARR, a citizen of the United States, residing in New York, in the borough of Brooklyn and State 5 of New York, have invented certain new and useful Improvements in Combination Traveling-Cases and Sales-Tables, of which the following is a specification.

This invention relates to an improved 10 traveling or other case which is intended for the use of tourists, peddlers, shoe-blacks, and others and which combines the advantages of a traveling-case for packing and storing the articles with a sales-stand, combining a 15 seat, table, sunshade, &c., for exposing the articles for sale, the table, sunshade, &c., being placed in the case after use; and for this purpose the invention consists of a combined traveling-case and sales-stand comprising a 20 case, a detachable frame in said case composed of end walls and corner-stays, a detachable standard supported on one of the stays, a detachable table supported on the standard, and a sunshade, also supported on the stand- 25 ard above the table.

The invention consists, further, of certain details of construction, which will be herein-after described, and finally pointed out in the claims.

30 In the accompanying drawings, Figure 1 represents a perspective view of my improved traveling-case shown in position for use as a sales-stand with table and sunshade supported by the same. Fig. 2 is a perspective view of the traveling-case with the supporting-standard for the table in position thereon. Fig. 3 is a vertical transverse section on line 3 3, Fig. 1. Fig. 4 is a horizontal section on line 4 4, Fig. 1, drawn on a larger 35 scale; and Fig. 5 is a perspective view of the supporting-standard shown as detached from the case.

Similar letters of reference indicate corresponding parts in the different figures of the 40 drawings.

In the drawings, *a* represents the body of a traveling-case, preferably of that class which telescopes into a cover *a'* and which is held together by means of straps *b* and carried by 45 a handle *b'*. The body *a* of the traveling-case is reinforced by a detachable frame composed of end walls *d*, which are connected at the corners by stays *d'*, that are made of wood, steel tubing, or other suitable material, so as to reinforce the end walls of the frame and the end walls of the body *a* and

impart sufficient strength to the latter for permitting the use of the traveling-case as a seat when the same is placed in upright position, so as to rest on its end, as shown in 60 Figs. 1 and 2. In line with one of the corner-stays is arranged in one of the end walls an opening *o*, so as to permit the insertion of the lower end of an upright standard *e* into the tubular end of one of the stays *d'*. The 65 standard *e* is provided near its lower end with an outwardly-bent U-shaped part *e'*, so that the standard itself is offset somewhat and can be moved out of the plane of the traveling-case to give the full end wall for seating purposes. The upper end of the standard *e* is provided with a horizontal portion *e*², which is bent integrally with the standard into oval or circular shape, as shown clearly in Figs. 2 and 5. The horizontal portion *e*² of the 70 standard *e* serves for supporting two perforated cross-strips of sheet metal *f*, said strips being supported at right angles to each other on the horizontal portion *e*² for the purpose of supporting a table *g*, as shown in Fig. 1, said 75 table being provided with a center hole for this purpose. The table is preferably provided with a rim and serves for the purpose of placing the articles that are to be sold on the same, the rim retaining them on the table 80 and preventing their dropping off from the same.

The traveling-case *a'*, with the table supported thereon, forms a sales-stand for the peddler for selling his wares, while the case 90 itself is used as a seat when the standard and table are placed in position thereon. When the stand thus obtained is exposed to the sun, a sunshade *h* is used by inserting the upper end *e*³ of the standard into the tubular end of 95 the stick *h'* of the sunshade *h*, as shown in Fig. 1. The sunshade on being folded up can either be carried in the hand or placed into the traveling-case, in which case the stick has to be of a less length than the length 100 of the case. When the day's work is done, the sunshade, table, and standard are removed and replaced with the unsold wares into the case, which is then closed, so as to be conveniently carried. 105

The standard, table, and sunshade form with the case a sales-stand which can be used by peddlers and others for selling small articles of merchandise or by bootblacks for storing their implements or by tourists and others, as it combines the advantages of a seat, table, and sunshade with the conven- 110

ience of a case for storing all these articles when going to or returning from the place of use.

Having thus described my invention, I claim as new, and desire to secure by Letters Patent—

1. The combination with a traveling-case, of a detachable frame the end walls of which are reinforced by corner-stays, a standard supported on one of said stays, and a table supported on said standard.

2. The combination with a traveling-case, of a detachable frame provided with end walls and supporting-stays for said end walls, a standard inserted into one of said stays and provided with a horizontal portion, and a table supported on said horizontal portion.

3. The combination with a traveling-case, of a detachable frame with reinforced end walls and corner-stays, a standard inserted into one of the corner-stays, said standard being provided with a bent horizontal portion, cross-strips supported on said horizontal portion, and a table supported on said strips.

4. The combination with a traveling-case, of a detachable frame having reinforced end walls, corner-stays for said end walls, a de-

tachable standard inserted into one of said stays, a table supported on said standard, and a sunshade also supported on the standard above the table.

5. The combination with a traveling-case, of a detachable frame provided with reinforced end walls and stays between said end walls, a detachable standard supported at its lower end in one of the stays, the lower part of the standard being provided with a horizontally-bent portion, and a table supported thereon.

6. The combination with a traveling-case, of a detachable frame composed of reinforced end walls and corner-stays for said end walls, one of said stays being tubular, and one of the end walls of the case being provided with an opening in line with the tubular corner-stay for inserting the lower end of a table-supporting standard.

In testimony that I claim the foregoing as my invention I have signed my name in presence of two subscribing witnesses.

NATHAN M. BARR.
